Des. 229,309

Patented Nov. 20, 1973

229,309

FILTERING UNIT FOR A SWIMMING POOL

Norbert L. Reiner, Wallingford, Conn., Donald Huffman, Montreal, Quebec, Canada, and Joseph Diemond, Simsbury, Conn., assignors to Colesco Industries, Inc., Hartford, Conn.

Original design application Oct. 22, 1970, Ser. No. 25,603, now Patent No. 223,449. Divided and this application Nov. 26, 1971, Ser. No. 202,729

Term of patent 14 years

Int. Cl. D23—01

U.S. Cl. D23—4

FIG. 1

FIG. 2

FIG. 5

FIG. 6

FIG.3

FIG.4

FIG. 1 is a side elevational view of a filtering unit for a swimming pool showing the new design;

FIG. 2 is a front elevational view thereof;

FIG. 3 is a rear elevational view thereof;

FIG. 4 is an elevational view of the side opposite that illustrated in FIG. 1;

FIG. 5 is a top plan view thereof; and

FIG. 6 is a bottom plan view thereof.

The conventional electric cord has been fragmentarily illustrated in FIGS. 1-4 and 6, and omitted from FIG. 5 for convenience of illustration.

This is a division of design application Ser. No. 25,603, filed Oct. 22, 1970, now Design Pat. No. D-223,449, issued Apr. 18, 1972.

We claim:

An ornamental design for a filtering unit for a swimming pool, as shown.
